UNITED STATES PATENT OFFICE.

CARL ROEHL, OF LOCKPORT, NEW YORK.

HORSE-COLLAR.

SPECIFICATION forming part of Letters Patent No. 245,869, dated August 16, 1881.

Application filed May 24, 1881. (No model.)

To all whom it may concern:

Be it known that I, CARL ROEHL, of Lockport, in the county of Niagara and State of New York, have invented new and useful Improvements in Horse-Collars, of which the following is a specification, reference being had to the accompanying drawings.

This invention relates more particularly to that class of horse-collars which are composed of several parts adjustably connected with each other in such manner that the size of the collar can be increased or reduced at desire to fit the animal on which the collar is intended to be used.

15 The object of this invention is the construction of a light and strong collar of this character which is readily adjusted and which readily adapts itself to the movements of animals.

20 My invention consists of the particular construction of the parts which compose my improved collar, as hereinafter fully set forth.

25 In the accompanying drawings, Figure 1 is a front view, partly in section, of a horse-collar provided with my improvements. Fig. 2 is a side elevation thereof. Fig. 3 is a side view of the upper portion of one of the side pieces of the collar. Fig. 4 is a cross-section, on an enlarged scale, in line $x-x$, Fig. 1. Fig. 5 is a vertical section on an enlarged scale, showing 30 the means whereby the hame-eye is adjustably secured to the collar. Fig. 6 is a cross-section in line $y-y$, Fig. 5. Fig. 7 is a cross-section through the collar-pad provided with an air-cushion. Fig. 8 is an elevation, showing that 35 side of the collar-pad which lies next to the hame-plate.

Like letters of reference refer to like parts in the several figures.

40 A represents two metallic hame-plates, preferably constructed of thin sheet-steel; and B are the hames, cast of malleable iron or other suitable metal, and secured to the plates A by rivets.

45 Represents short extensions or upward continuations of the hames B, which are adjustably secured to the upper ends thereof, and provided on their inner sides with plates D, forming upward continuations of the hame-plates A, and resting against the outer sides of the 50 upper portions of the plates A and hames B.

The extensions C of the hames are hinged together at their upper ends, as shown at c , preferably by a removable pintle or pivot-bolt, which is fastened in place by a screw-nut or otherwise, so that the two parts can be readily 55 separated should it become necessary to renew either part. The upper portion of each hame B is provided on its inner side with a longitudinal depression or groove, b , which terminates near the upper end of the hame in an 60 opening, b' , and the plate A is provided with a similar depression, a , which coincides with the depression b of the hame. The space which is so formed between the hame B and the plate A secured thereto is sufficient to accommodate 65 the nut e of the screw-bolt e' , whereby the upper extensions are secured to the lower main portions of the hame. The groove b in the hame is preferably provided with serrations, as shown in Fig. 1, and the nut e is provided with corresponding serrations, which enter the serrations of the hame and prevent the nut from slipping. The nut e is introduced into the groove between the hame and the plate through the opening b' . The hame is provided 70 with a longitudinal slot, f , through which the threaded inner end of the bolt e' projects into the groove b , and in which the bolt e' can be raised and lowered when it is required to adjust the upper part of the collar. The outer 75 end of the bolt e' is provided with a head, e^2 , having a perforation, in which a pin may be inserted for turning the bolt; or it may be made of square or other suitable form adapted 80 to be turned by a wrench. 85

The upper portion of the hame B is provided with marginal flanges g , whereby it is secured to the plate A, as shown in Fig. 3.

85 The plates D are provided with depressions or grooves to fit over the outer sides of the 90 upper portions of the hames B and plates A, as shown in Fig. 4. The extensions C of the hames B are riveted to the plates D. The fastening-bolts e' project inward through an opening in the hame-extensions D and plates 95 C, as shown in Figs. 1 and 4, and are secured in place by screwing them into the nuts e .

G represents a terret attached to each hame-extension D in a common and well-known manner.

h represents the hame-eye, to which the tug is attached, and *h'* a similar eye, to which the martingale is attached. Both eyes are cast with a shank, *H*, which is grooved on its inner side, as shown in Fig. 6, so as to fit over and slide on the hame *B*. The latter is provided with a longitudinal depression, *i*, arranged at its inner side at the height at which the hame-eye is usually attached, and with a longitudinal slot, *i'*, extending nearly to the ends of the depression or groove *i*.

The shank *H* is secured to the hame by a bolt, *k*, which is provided with a perforated head, and which engages with its inner threaded end in a screw-nut, *k'*, which is arranged in the groove *i* of the hame.

The plate *A* is provided with a depression coinciding with the groove *i* to accommodate the nut *k'*, as shown in Figs. 5 and 6. The groove *i* is preferably provided with serrations on both sides of the slot *i'*, and the nut *k'* with corresponding serrations, whereby the nut is prevented from slipping.

m represents an opening formed in the side of the hame and communicating with the depression *i* to permit the introduction and removal of the nut *k'*. Upon loosening the bolt *k* the hame-eye can be raised or lowered on the hame within the length of the slot *i'*, as may be required.

The lower ends of the hames *B* are connected by a locking device, *N*, composed of two parts, one attached to each hame, and adapted to be readily locked and unlocked for securing or separating the lower ends of the hames, as may be desired. Each half of the locking device is provided with a flange, *n*, which is adjustably secured to the lower end of the hame by a screw-bolt, *o*. The latter engages

with its inner threaded end in a screw-nut, *o'*, which is arranged in a groove, *p*, formed on the upper side of the lower end of the hame. The latter is provided with a slot, *p'*, running lengthwise of the groove *p*, and in which the bolt is

adjustable. The flange *n* is provided with a hole, through which the bolt *o* projects into the groove *p*. The adjacent sides of the groove *p* and nut *o'* are preferably serrated to prevent the nut from slipping. The groove *p* extends

to the end of the hame, and thereby permits the ready introduction and removal of the nut into and from the groove.

The upper portions, *C D*, of the collar are by the above-described means readily adjusted to increase or reduce the height of the collar, and the two parts of the locking device *N* are readily adjusted to increase or reduce the width of the collar, and the latter is by this means readily adjusted to fit the horse on which it is used.

The employment of the metallic hames and hame-extensions permits the use of very light hame-plates, and renders the collar very light and at the same time sufficiently strong.

Q represents the pads or cushions which are attached to the inner sides of the plates *A*.

These cushions are composed of a back, *q*, of pasteboard or other suitable stiff material, lying next to the plates *A*, and an inner lining of leather, *q'*, the edges of which are turned outward and sewed to the edges of the back *q*. The latter is provided with holes *r* for the introduction of the material with which the cushions are filled. The cushions are secured to the plates *A* by turning and closing the edges of these plates over the edges of the back and lining of the cushion, as represented in Figs. 4, 6, and 7.

S represents an air-cushion, made of india-rubber, and placed between the back *q* and the lining *q'* of each cushion before these parts are sewed together. The material with which the cushion is stuffed is then introduced through the openings *r*, between the back *q* and the air-cushion, whereby the latter is pressed against the lining *q'*. The air-cushion imparts elasticity to the pad, and enables the latter to adapt itself to the varying form of the shoulder of the animal during the movements of the latter in drawing, and distributes the pressure evenly over the entire bearing-surface.

t represents pads secured with their upper portions to the inner sides of the extension-plates *D*, and having their tapering lower portions held in place by straps *t'*.

I claim as my invention—

1. In a horse-collar, the combination, with metallic hame-plates *A* and hames *B*, secured thereto and provided with a locking device, *N*, whereby their lower ends are connected, of the extension-plates *D* and hame-extensions *C*, secured together and attached adjustably to the parts *A B*, the upper ends of the hame-extensions *C* being connected by a hinge, substantially as set forth.

2. In a hame collar, the combination, with the plate *A*, of the hame *B*, provided with depression *b* and slot *f* for adjusting the bolt *e*, substantially as set forth.

3. In a horse-collar, the combination, with the plate *A*, of the hame *B*, provided with the depression *b*, terminating in an opening, *b'*, through which the screw-nut *e'* is inserted and removed, substantially as set forth.

4. In a horse-collar, the combination, with the plate *A* and hame *B*, provided on their adjacent sides with depressions *a b* and a slot, *f*, formed in the hame, of the extension-plate *D*, fitted against the outer side of the plate *A* and hame *B*, a hame-extension, *C*, secured to the plate *D*, and a screw-bolt, *e*, passing through the parts *C D* and slot *f*, and having its screw-nut *e'* arranged in the depressions *a b*, substantially as set forth.

5. The combination, with the hame *B*, provided on its rear side with a depression, *i*, and having a slot, *i'*, of a hame-eye cast with a shank, *H*, which fits over the outer side of the hame, and a fastening-bolt, *k*, passing through the shank *H* and slot *i'*, and secured in place by a nut, *k'*, arranged in the depression *i*, substantially as set forth.

6. The combination, with the plate A, of a hame, B, provided with a groove, *i*, on its rear side, and a lateral opening, *m*, through which the nut *k* can be introduced in the groove *i*, substantially as set forth.
7. The combination, with the hames B, of a fastening device each part of which is provided with a flange, *n*, grooves *p*, formed in the upper or rear sides of the hames and extending to their ends to form openings for the introduction of the screw-nuts *o*', slots *p*', formed in the hames, and screw-bolts *o*, whereby the flanges *n* are adjustably secured to the hames, substantially as set forth.
8. The combination, with the pads Q, of the plates A, having their edges bent or closed over the projecting edges of the pads, substantially as shown and described.
9. In a horse-collar, a pad provided with a back, *q*, having openings *r* for the introduction of the stuffing material, substantially as set forth.
